UNITED STATES PATENT OFFICE.

JOHN McNAUGHTON, OF NEW YORK, N. Y.

MOP.

1,391,132.

Specification of Letters Patent. Patented Sept. 20, 1921.

Application filed October 8, 1920. Serial No. 415,569.

To all whom it may concern:

Be it known that I, JOHN McNAUGHTON, a subject of the King of England, residing at New York, in the county of New York and 5 State of New York, have invented a new and useful Mop, of which the following is a specification.

This invention relates to a mop, one of its objects being to provide a structure which 10 can be cheaply made out of sheet metal and which, when the parts are assembled, will provide means whereby the cloth of the mop can have the water pressed therefrom quickly after which the cloth can be readily 15 placed in operative position upon the mop head.

A further object is to provide a cloth of novel construction having means whereby it can be readily placed in position on the mop 20 head, said means being so shaped as to be held to the handle of the mop while the mop is in use.

A further object is to provide a novel arrangement of parts for holding the cloth 25 of the mop under compression, the various parts of the mop head being easily assembled and being held against accidental displacement even though roughly handled.

With the foregoing and other objects in 30 view, which will appear as the description proceeds, the invention resides in the combination and arrangement of parts and in the details of construction hereinafter described and claimed, it being understood 35 that, within the scope of what is claimed, changes in the precise embodiment of the invention shown can be made without departing from the spirit of the invention.

In the accompanying drawings the preferred form of the invention has been shown.

In said drawings—

Figure 1 is a view partly in side elevation and partly in section of a mop embodying the present improvements.

Fig. 2 is a side elevation of the mop head, the housing of the spring being removed.

Fig. 3 is a transverse section through one side portion of the mop head and showing the housing of the spring in position.

Fig. 4 is a perspective view of the housing for the spring.

Fig. 5 is a plan view of the blank from which the cross member of the mop head is formed.

Fig. 6 is a perspective view of the blank after the second step of the forming operation.

Fig. 7 is a perspective view of the completed cross strip of the head.

Fig. 8 is a transverse section through the 60 reduced portion of the mop handle and showing the cloth holding means in position.

Referring to the figures by characters of reference 1 designates a blank of sheet metal substantially oblong and which, in the first 65 step of manufacture, is formed with a central longitudinal slit 2, short transverse slits intersecting the end portions of the slit 2, as shown at 3, and central and side lugs 4 at each end. In the second step of the method 70 of making the cross strip of the mop head the middle portion of the strip is depressed to substantially semicylindrical form as shown at 5 in Fig. 6. By a third step of 75 the process the said blank is folded longitudinally so as to produce a central slit sleeve 6 having oppositely extending channeled wings 7, this sleeve and the wings making up the complete cross strip of the mop head.

The front and sides of the mop head are stamped from a single strip of metal shaped to form a front cross strip 8 having an outwardly curved lip 9 along the lower edge thereof and an outwardly extended flange 85 10 along the upper edge thereof. The sides 11 of the mop head formed by this strip are outwardly turned at their lower edges, as shown at 12 and are formed with longitudinal slots 13 made by striking out flanges 14. These 90 flanges diverge outwardly as shown particularly in Fig. 3. An ear 15 is struck outwardly from one end of the slots 13 and both the flanges 14 and the ear 15 are adapted to be engaged by a substantially cylindrical 95 housing 16 one end of which is closed as shown at 17 while a slot 18 is extended longitudinally of the housing and is adapted to receive the flanges 14. Thus by sliding the housing 16 longitudinally onto the flanges 14 100 and against the ear 15 the side of the mop head and the housing 16 will be securely connected together.

A roller 18 is mounted between the sides 11 of the mop head and has gudgeons 19 105 projecting from the ends thereof into the respective slots 13 so as to extend loosely into the housing 16 and bearing against each of these gudgeons 19 is a button 20 having a stem 21 which projects into one end of a 110 coiled spring 22. This coiled spring is loosely mounted in the housing 16 and bears at its other end against the ear 15. Thus it will be seen that the spring presses the but-

ton firmly against the adjacent gudgeon 19 so that the roller 18 is thus held pressed toward the front strip 8 of the mop head.

Notches 23 are formed in the rear portion 5 of each of the sides 11 and are adapted to receive the lugs or studs 4 formed upon the ends of the cross strips 6-7.

The split sleeve 6 is adapted to receive one 10 end of a mop handle 24, this handle having an annular reduced portion 25 close to the sleeve.

The mop cloth 26, which can be of any 15 suitable material, is extended through a loop or ring 27 of wire or the like, a portion of this loop being pressed inwardly as at 28 thus to form oppositely disposed finger pieces or loops 29 which converge toward each other to form a clip indicated generally at 30.

20 In using the device herein described the ring 27 is forced between the strip 8 and the roller 18 so that the finger pieces 29 will project upwardly from the mop head. The user then grasps these upwardly projecting portions 29 and pulls the ring 27 from 25 between the roller 18 and the strip 8 and drops the clip portion 30 of the ring onto the reduced part 25 of the handle of the mop. The ring will slip along this reduced portion 30 and will ultimately gravitate onto the end portion of the handle close to the mop head where it will be securely held in place. The mop cloth will extend over the mop head as shown and will project downwardly a 35 considerable distance from the head where it can be used like an ordinary mop cloth. When it is desired to extract water from the mop cloth the ring 27 is pulled upwardly onto and then off of the reduced portion 25 40 of the handle thus disengaging the two parts. The ring is then used as a handle for pulling the mop cloth from position between the roller 18 and the strip 8 with the result that water will be extracted from the cloth. The 45 cloth can then be reinserted into the mop head in the manner hereinbefore pointed out.

What is claimed is:

1. In a mop the combination with a front cross strip having side portions extending 50 therefrom provided with notches in their free ends, of a cross strip including a central split sleeve and oppositely extending channel portions, lugs projecting from said channeled portions and seated in the notches, 55 diverging retaining flanges extending longitudinally along the side strips, there being a slot therebetween, a housing slidably longitudinally in engagement with the flanges and held to the side strip thereby, a spring 60 within the housing, an expressing roller having gudgeons projecting into the slots in the side portions, said springs thrusting against the gudgeons, and a handle seated within 65 and extending from the split sleeve.

65 2. In a mop a front cross strip having

side portions formed on said side portions integral therewith and provided with notches in their free ends and longitudinal slots, outwardly diverging flanges along the sides of the slots, an outwardly projecting 70 ear at one end of each slot, housings slidably engaging the flanges for covering the slots, a roller between the side portions and having gudgeons slidably and revolvably mounted in the slots, springs within the housings, each 75 spring bearing at one end against an ear and thrusting at its other end against a gudgeon, said springs coöperating to press the roller normally against the front strip, and a back cross strip folded longitudinally and 80 comprising a central split sleeve and oppositely extending channel portions, and lugs upon the channel portions seated in the notches of the side portions.

3. In a mop the combination with a mop 85 head having a front cross strip, side portions extending therefrom and integral therewith, and a rear cross strip connected to the side portions, said strips and side portions being formed of sheet metal, of a roller 90 slidably and revolvably mounted between the side portions, means for holding the roller yieldingly pressed toward the front cross strip, a handle extending from the rear cross strip and having an annular reduced portion, 95 a mop cloth, and a ring engaged by the mop cloth and having an inwardly extended portion constituting a clip for embracing the reduced handle portion.

4. In a mop the combination with a handle 100 having an annular reduced portion, of a mop head consisting of a front strip having side portions integral therewith and provided with notches in the free ends of the side portions, a back strip including a central split sleeve and oppositely extending channel portions, lugs upon said channel portions seated within the notches to hold the side portions and back strip assembled, there being longitudinal slots in the side 105 portions, outstanding flanges along the sides of the slots, a housing slidably engaging and retained by the flanges, an outstanding ear upon each side portion constituting a closure for one end of the housing, springs bearing 110 against the ears and within the housing, buttons engaged by the springs, a roller interposed between the side portions, gudgeons extending therefrom and into the slots, said 115 gudgeons being engaged by the buttons, and a mop cloth insertible between the roller and the front cross strip.

In testimony that I claim the foregoing as my own, I have hereto affixed my signature in the presence of two witnesses.

JOHN McNAUGHTON.
